(57) **CLAIM**

The bottle, substantially as shown and described.

DESCRIPTION

FIG. 1 is a front elevational view of the present invention.

FIG. 2 is a back elevational view thereof.

FIG. 3 is a left side elevational view thereof, the right side elevational view being a mirror image.

FIG. 4 is a top plan view thereof; and,

FIG. 5 is a bottom plan view thereof, where all but the outer edge of the bottom forms no part of the claimed design.

The broken line showing of a portion of the bottom is included for the purpose of illustrating environmental structure and forms no part of the claimed design.
